UNITED STATES PATENT OFFICE.

THOMAS HENRY MAPP, OF SURRY HILLS, NEAR SYDNEY, NEW SOUTH WALES, AUSTRALIA.

HYDRAULIC PRESS.

No. 876,821.

Specification of Letters Patent.

Patented Jan. 14, 1908.

Application filed August 6, 1906. Serial No. 329,465.

To all whom it may concern:

Be it known that I, THOMAS HENRY MAPP, a subject of the King of Great Britain, residing at 382 Bourke street, Surry Hills, 5 near Sydney, State of New South Wales, Australia, have invented certain new and useful Improvements in Hydraulic Presses, of which the following is a specification.

This invention relates to improvements in 10 hydraulic presses in which the material to be compressed is fed into a bottom box and is then forced upwardly into an upper box where the compression takes place.

The object of the invention is to simplify 15 the construction and working of such presses.

According to my invention the top box is movable vertically on the head of the press by means of two double acting plungers 20 which raise and lower said box and also prevent its shifting when the ram acts to compress the material against the head of the press.

Referring to the accompanying drawings, 25 Figure 1 is a perspective view illustrating my improvements. Fig. 2 is a partial sectional elevation, and, Fig. 3 is a sectional plan on line 3—3 Fig. 2.

On the base 4 are columns 5 supporting 30 the top plate 6 carrying the head 7 of the press. The head has a feed opening 8 provided with a slide 9 to open and close same. On the head 7 also slides vertically the top box 10 which is secured to the piston rods 35 11 operated by the plungers in the double acting cylinders 12 the latter having the branched supply pipes 13 and 14. The piston rods have guides in the brackets 15 which are bolted to the columns 5, the cylinders being secured to the base 4 by means of 40 bolts 16. Resting on the base 4 is the main cylinder 17 with its ram 18 and supply pipe 19. The head 20 of the ram slides within an open ended bottom box 21 which is supported to the cylinders 12 and to the brackets 45 15 by bolts 22.

In operating a press fitted with my improvements the top box 10 is raised to its highest position by the piston rods 11 being 50 forced up by water entering the cylinders 12 through the pipes 14 thereby allowing the slides 9 to be withdrawn as shown in Fig. 1. While the ram head 20 stands at its lowermost position, the material to be 55 pressed is fed through the opening 8 and falls

into the bottom box 21. On there being sufficient material in the bottom box to form a block of the desired size, the slide 9 is pushed in so that the handle is flush with the side. Water is now passed through the 60 pipes 13 to depress the piston rods 11 thereby lowering and retaining top box 10 in position on the bottom box 21, while the ram 18 compresses the material into a block 23 (Fig. 2) which is held together by means 65 of clamps passing through the slots 24.

As usual plates are placed immediately below and above the material before compression.

To remove the block the water in the upper 70 ends of the cylinders 12 is allowed to discharge and water is passed in to the lower ends through pipes 14 thereby raising the piston rods and lifting the box 10 clear of the bottom box and compressed block which can 75 now be removed when the press is ready for another charge. It is evident that the pipes 13 and 14 may act both for the supply and discharge of the water from the cylinder 12.

Having now described my invention what 80 I claim as new and desire to secure by Letters Patent is:—

1. In a hydraulic press, the combination of a press head, a top box vertically movable on the head, a fixed bottom box over which the 85 top box is also vertically movable, means in the bottom box for compressing the material in the top box, and means for moving the top box and for holding the latter in rigid relation to the top of the fixed bottom box. 90

2. In a hydraulic press, the combination with a fixed bottom box, of a press head disposed over the upper extremity of the bottom box, a top box vertically movable on the head and over the upper extremity of the bottom box, a main ram movable in the bottom box and operative to force the material into the top box, and double acting cylinders having plungers provided with piston rods secured to the top box, the top box being held 100 fixed on the upper extremity of the bottom box for an interval by the plungers and piston rods of the said cylinders, and raised vertically by the plungers and piston rods to leave the compressed material exposed for 105 removal.

3. In a hydraulic press, the combination with a bottom box, a press head disposed over the upper extremity of the bottom box, a top box slidable on the press head and conjunc- 110

tively operative with the upper end of the bottom box, a cut-off slide mounted in the top box, a main ram in the bottom box, and double acting cylinders having plungers provided with piston rods connected to the top box.

In testimony whereof I have hereunto set

my hand in presence of two subscribing witnesses.

THOMAS HENRY MAPP.
